UNITED STATES PATENT OFFICE.

LANE JOHNSON, OF PITTSBURGH, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

ROLLING-MILL-SPINDLE COUPLING.

Application filed September 12, 1924. Serial No. 737,278.

To all whom it may concern:

Be it known that I, LANE JOHNSON, a citizen of the United States, residing at Pittsburgh, county of Allegheny, and State of Pennsylvania, have invented a new and useful Improvement in Rolling-Mill-Spindle Couplings, of which the following is a full, clear, and exact description.

The present invention relates to universal 10 couplings, and particularly to the universal couplings which connect the spindles to the driving pinions and rolls of a rolling mill of the type, for example, disclosed in the patent to Geer, No. 1,041,773.

15 In universal couplings of this character, difficulty is experienced due to the fact that when the spindle end is uncoupled from the pinion or roll neck, the slippers are free to turn relatively to each other. Any relative 20 turning movement between the slippers places their opposed flat interior surfaces out of parallelism. When this happens considerable trouble is occasioned in readjusting the slippers so as to bring their opposed 25 flat faces into parallel relation to permit the projections on the end of the spindle to slide in between these surfaces. By the present invention I overcome this difficulty by journaling on the cylindrical spacer 30 block arranged between the slippers means which slidably fits the opposed faces of the slippers and prevents relative rotary movement between said slippers when the spindle is uncoupled from the pinion or roll neck, 35 as the case may be, but which at the same time permits the slippers to rotate together about the axis of the spacer block as usual when the coupling is in operation.

In the accompanying drawings, wherein 40 I have illustrated a preferred embodiment of the invention,—

Figure 1 is a view, partly in section, of the coupling between the end of a spindle and a roll neck or driving pinion, the section being taken on the line I—I of Figure 2 and along a plane at right angles to the axis of the coupling bolt;

Figure 2 is a view, partly in section, of the coupling, the section being taken on the line II—II of Figure 1 and along a plane containing the axis of the coupling bolt;

Figure 3 is a transverse sectional view on the line III—III of Figure 2, and

Figure 4 is a sectional view of the coupling elements assembled.

In the illustrated embodiment of my invention, 2 designates the bifurcated end of either a roll neck or a driving pinion, and 3 the end of a spindle. The bifurcated end 2 has opposed concave interior surfaces 4 forming portions of a cylindrical surface, the axis of which intersects the axis of rotation of the part 2 and extends at right angles thereto. Seated in these concave surfaces are the slippers 5 which have convex 65 surfaces corresponding thereto. Each slipper has a central rib 6 of convex form fitting in a central concave depression 7 of the corresponding concave surface 4. This construction permits the slippers to rock in their seats about the axis of the concave surfaces 4, but prevents movement of said slippers in a direction parallel to said axis.

The spindle end 3 is provided with spaced integral projections 8 of substantially rectangular form in cross section. These projections make a sliding fit with the opposed flat interior faces 9 of the slippers 5. Arranged between the slippers is a cylindrical spacer block 10 having a hole 11 therethrough at right angles to its axis. A bolt 12 passes through the bifurcated end 2 and also through elongated holes 13 in the slippers. The spacer block is journaled on the central portion of the bolt between the 80 slippers.

The construction so far described is substantially identical with the construction shown in the Geer patent above referred to, except that in the construction shown in the 90 patent the flat ends of the cylindrical spacer block slidably engage the opposed flat interior surfaces of the projections on the spindle end, whereas in the present construction the ends of the spacer block 10 do not engage the flat interior faces of the projections 8.

As heretofore stated, in the coupling construction of the type shown in the Geer patent, when the spindle is disconnected 100 from the driving pinion or roll neck, the slippers are free to turn relatively to each

other, because the cylindrical spacer block does not prevent such relative turning movement. In order to overcome this difficulty, I journal upon the spacer block 10 a box-like element 14 which is divided centrally into two parts to permit the element to be mounted on the spacer block. This element comprises two flat end plates 15 engaging the flat ends of the spacer block and adapted 10 to slidably engage the opposed flat interior faces of the projections 8. The plates 15 are provided with flanges 16 having concave cylindrical surfaces 17 engaging the cylindrical surface of the spacer block. The flanges 16 on one of the plates 15 are provided with central projections 18 adapted to fit in central recesses 19 in the flanges of the other plate. When the two parts of the box-like element are mounted on the spacer 20 block these parts are adapted to be rigidly fastened together by means of rivets 20 passing through the flanges 16.

It will be apparent, by reference to Figure 2, that the box-like element 14 journaled on the spacer block 10 permits the coupling to function in the usual manner, the same as in the construction illustrated in the Geer patent referred to. However, this box-like element prevents any relative rotary movement 30 between the slippers 5 when the spindle is uncoupled from the roll neck or driving pinion.

While I have illustrated and described my invention in connection with the universal coupling between a spindle end and a driving pinion or roll neck, it will be understood that the invention is not limited to such application thereof, but that this improved universal coupling may be employed for coupling 40 any two rotary elements. Moreover, while I have illustrated and described the preferred embodiment of my invention, it will be understood that the invention is not limited to the details of construction shown, 45 but may be otherwise embodied within the scope of the appended claims.

I claim:

1. In a coupling, a rotary member provided with a pair of projections at one end 50 thereof, a second rotary member having a bifurcated end adapted to receive said projections, said bifurcated end having its opposed interior surfaces of concave cylindrical form, slippers seated within said concave surfaces to turn about the axis thereof and slidably fitting said projections, a cylindrical spacer block arranged between said slippers with its axis intersecting said projections, and means journaled on said block 55 and adapted to prevent relative rotary movement between said slippers when said rotary members are uncoupled, substantially as described.

2. In a coupling, a rotary member provided with a pair of projections at one end 60

thereof, a second rotary member having a bifurcated end adapted to receive said projections, said bifurcated end having its opposed interior surfaces of concave cylindrical form, slippers seated within said concave surfaces to turn about the axis thereof and slidably fitting said projections, a cylindrical spacer block arranged between said slippers with its axis intersecting said projections, and means journaled on said block 70 and adapted to prevent relative rotary movement between said slippers when said rotary members are uncoupled, said means slidably engaging the opposed interior faces of said projections, substantially as described. 80

3. In a coupling, a rotary member provided with a pair of projections at one end thereof, a second rotary member having a bifurcated end adapted to receive said projections, said bifurcated end having its opposed interior surfaces of concave cylindrical form, slippers seated within said concave surfaces to turn about the axis thereof and slidably fitting said projections, a cylindrical spacer block arranged between said slippers with its axis intersecting said projections, means journaled on said block and adapted to prevent relative rotary movement between said slippers when said rotary members are uncoupled, and a bolt passing transversely through said spacer block, said slippers and said bifurcated end, substantially as described. 85

4. In a coupling, a rotary member provided with a pair of projections at one end 100 thereof, a second rotary member having a bifurcated end adapted to receive said projections, said bifurcated end having its opposed interior surfaces of concave cylindrical form, slippers seated within said concave surfaces to turn about the axis thereof and slidably fitting said projections, a cylindrical spacer block arranged between said slippers with its axis intersecting said projections, and means journaled on said block 105 and adapted to prevent relative rotary movement between said slippers when said rotary members are uncoupled, said means comprising end plates rigidly connected together and engaging the ends of said spacer block 110 and slidably engaging the opposed interior faces of said projections, substantially as described. 115

5. In a coupling, a rotary member provided with a pair of projections at one end 120 thereof, a second rotary member having a bifurcated end adapted to receive said projections, said bifurcated end having its opposed interior surfaces of concave cylindrical form, slipper seated within the said concave surfaces to turn about the axis thereof and slidably fitting said projections, a cylindrical spacer block arranged between said slippers with its axis intersecting said projections, and 125

130

means journaled on said block and adapted to prevent relative rotary movement between said slippers when said rotary members are uncoupled, said means comprising plates ¹⁰ 5 gaging the ends of said spacer block, opposed flanges on said plates having concave surfaces fitting the cylindrical surface of said spacer block, and means extending through said flanges and rigidly connecting said plates together, substantially as described..

In testimony whereof I have hereunto set my hand.

LANE JOHNSON.
